INSULATING COVERING

Fridolf Henning Brunnzell, Sundsvall, Sweden

Application July 29, 1947, Serial No. 764,518
In Sweden March 16, 1945Section 1, Public Law 690, August 8, 1946
Patent expires March 16, 1965

10 Claims. (Cl. 154—44)

1

This invention relates to insulating coverings, more particularly heat-insulating jackets of the kind in which a layer of a material possessing good insulating properties, or low heat conducting properties, preferably a porous, and usually a fibrous material such as glass wool or the like, is covered over with a protective covering. As is well known, insulating jackets of this kind are employed for cisterns, boilers, steam accumulators, pipe-lines and the like, thermo-technical and chemico-technical apparatus and equipment.

In cases where it is permissible after taking into account the necessary resistance capacity to atmospheric, chemical and other influences, there has been a constantly increasing tendency in recent times to construct the protective jacket of metal plate, such as copper, aluminium, etc., since a construction of this kind has been found to give favourable results both from the point of view of assembly and maintenance. Thin fibre plates have also found an extensive use.

One object of the invention is to provide an insulating cover of this kind that is easy to manufacture and to attach to the wall to be insulated.

Another object of the invention is to decrease the heat losses due to the heat conductors formed by the means for attaching the insulating cover to the wall to be insulated.

The invention will be more particularly described herewith with reference to the accompanying drawings which show some forms of construction according to the invention by way of example.

Fig. 1 is a diagrammatic view of an insulating mat known per se which is provided with fixing devices in accordance with the invention.

Fig. 2 is a diagrammatic section along the line I—I in Fig. 1.

Fig. 3 illustrates a finished unit according to the invention with a metallic protective plate in section corresponding to a section along the line II—II in Fig. 1.

Figs. 4 and 5 show cross-sections of parts of a wall for a cylindrical container provided with a jacket in accordance with the invention.

Fig. 6 is a diagrammatic cross-section of the part shown in Fig. 4 with units of a somewhat different construction.

Figures 4-6 are not drawn to scale for the sake of clearness and for the same only the outer plates and their fixing members are shown but not the layer of insulating material.

Fig. 7 is a diagrammatic detail view of a cross-section through a joint between two outer plates in accordance with another form of construction.

2

Fig. 8 is a detail view similar to Fig. 7 of a joint in accordance with still another form of construction.

Fig. 9 shows part of a container fitted with a heat-insulating jacket built up from units in accordance with the invention.

Fig. 10 shows a specially favourable form of construction for the attachment of a fixing member to the protective plate of a unit.

Fig. 11 shows a further improvement of the arrangement according to Fig. 10 which is at the same time intended to serve for fixing the insulating mat to the protective plate.

Fig. 12 shows a section through a unit having a fixing device in accordance with Fig. 11.

If the protective plate consists of galvanised plate, black-oxidised plate or other metal plate, an insulating mat in accordance with Figs. 1 and 2 may suitably be used which consists, in a form known per se, of a glass wool layer 2 which is sewn fast by means of thin wire 3 to a foundation of metal wire netting 4. Between the glass wool layer and the netting 4 small strips 5 are inserted. To facilitate welding, these strips are preferably of the same material as the proposed protective plate. As may be seen from Fig. 3, the mat prepared in this manner is laid on the protective plate 6 with the wire netting 4 turned towards the latter, whereupon the strips 5 are connected to the protective plate 6 by a number of spot welding points 7.

It is also possible to attach the wire netting 4 directly to the protective plate by welding or soldering by which means the fixing strips 5 can be dispensed with. This is not to be recommended however, as the wire netting is usually so weak that there is a risk of its being burnt away so that no reliable connection is obtained. Furthermore, in the case of spot welding which is particularly suitable for the work in question, it is difficult to determine whether a point has been found with the electrode at which contact is actually established with the material of the netting. The straight strips employed according to the invention are easy to find however, particularly when the strip projects slightly at the sides, which is therefore recommended and is moreover indicated in Figs. 1 and 3. In this case it is only necessary to follow the course of the strip with the electrode.

The fixing strip 5 can, within the scope of the invention, also be fixed to the protective plate by soldering, riveting or by any other known means. It is also possible, for example to fix the strip merely by bending the projecting ends

of the strip around the edge of the protective plate. By this means it is possible to employ the construction described for an insulating mat which is attached to the protective plate by means of the said fixing strips even in cases where the protective plate does not consist of a metal plate but of some other material, such as fibre plates for example.

Figs. 4 and 5 illustrate the method of procedure when mounting a heat-insulating jacket on a cylindrical container, employing units in accordance with the invention. The wall of the container is indicated at 8. As shown in Fig. 4, a start is made with one unit which in accordance with the invention consists of a protective plate 9₁ of sheet metal with an insulating layer of glass wool placed on the latter. This glass wool layer is not shown in Figs. 4-6 for the sake of clearness. To the protective plate 9₁ the fixing members 10₁ are attached, each of which consists of an insulating intermediate part to each end of which a sheet metal strip bent at an angle is securely riveted. The intermediate part consists preferably of a material such as asbestos cement, synthetic resin, pressboard or the like while the two end members may be of a material which is suitable for fixing to the protective plate and the wall to be insulated respectively. The fixing members are attached at one end to the protective plate by spot welding and are located close to two opposite edges 9₁₁ and 9₁₂ of the plate, the said edges lying at right angles to the surface of the drawing, and two fixing members may suitably be placed at each edge. The fixing members are attached at the other end by spot welding to the wall 8 so that the first unit is firmly fixed to the wall, the glass wool layer thus being enclosed between the wall and the protective plate. For the second unit, one is selected as shown in Fig. 5, the protective plate 9₂ of which is preferably provided with two fixing members 10₂ at the one edge 9₂₂ only. The second unit is placed beside the first in such a manner that the edge 9₂₁ of this protective plate 9₂ opposite to the edge 9₂₂, will lie parallel with the edge 9₁₂ on the first unit's protective plate 9₁ and will project under the latter edge with a certain margin. The fixing member 10₂ is thereupon attached to the container wall by spot welding. The third unit with its protective plate 9₃ is fixed beside the second unit in a manner entirely similar to that employed for fixing the second unit beside the first. In the same way a row of units is built up to form a belt round the container, until only one single unit remains to close the belt.

Each of the units is held fast on one side by the fixing members, and on the other side by the projecting edge of the preceding unit's protective plate against which it is pressed by the elasticity of the glass wool layer.

The thickness of the glass wool layer and the length of the fixing member are adapted to one another with a view to the foregoing requirement.

As may be seen from Fig. 4, the last remaining unit has no fixing member. It is attached solely by pushing the two edges 9_{n1} and 9_{n2} of the protective plate 9_n under the edge 9_{(n-1)2} of the penultimate unit's protective plate 9_(n-1) and the edge 9₁₁ of the first protective plate 9₁. Here also the pressure of the elastic insulating material is employed to hold the unit in its position.

Alongside the finished belt a second belt is fixed in the same manner, and subsequently a

third belt, etc. In this respect the belts may either be made to abut against one another or overlap one another with a certain margin.

According to one very favourable feature of the invention the edges of the unit's protective plates which are intended to overlap one another are bent downwards or upwards in such a way that a raised edge always engages underneath a bent-down edge whereby the connection between the units in the finished insulating jacket is considerably improved. This arrangement is shown clearly in Figs. 4 and 5.

Alternatively, the protective plates for the units may be provided with folded edges by means of which the adjacent plates of the units may be hooked into one another so that they cannot be separated by forces directed at right-angles to the surface of the protective plates. This arrangement is shown diagrammatically in Fig. 6 where it is employed for the part shown in Fig. 4. It is adapted when the insulating material is not sufficiently resilient to hold the protective plate pressed against the overlapping edge in a reliable manner. In other respects also a stronger junction of the insulating covering is obtained with this arrangement.

The form of construction last described will of course be more expensive to manufacture. Furthermore, folds of this kind can only be produced advantageously with protective plates made of sheet metal. This arrangement will, however, only be employed in exceptional cases, and the arrangement shown in Fig. 4 with slightly bent edges will be found to meet the requirements satisfactorily in normal cases.

Fig. 7 shows a form of construction with another possible arrangement of joints between two adjacent units. The edge of a protective plate 9_(v+1) is inserted in the slot formed between the edge of the preceding protective plate 9_v and a slightly bent strip 9_{v2} which is rigidly welded or riveted to the aforesaid edge.

Fig. 8 shows a further form of construction for a joint in which the slot in Fig. 8 previously referred to is produced by means of a special, very narrow strip which also serves as a distance piece. The following plate is provided with a special strip mounted along the edge, which is intended to engage in the slot. The joint constructed in this manner is very similar to the joint according to Fig. 7, but, as is clearly shown, it possesses the great advantage that the units placed beside one another form a perfectly smooth surface without overlapping edges. This is of particular importance where value is placed on an attractive appearance and convenience in cleaning, as for example for refrigerators which are fitted with insulating coverings of stainless metal and the like.

In an insulating jacket of complete units according to the invention which are each mounted separately on the wall to be insulated the drawback is avoided that the edges of the plates in the protecting casing will be torn as in the previously employed arrangements for joining plates, such as plate metal screws or the like which was a disadvantage both from the point of view of appearance and durability.

It is essential for the invention that the fixing members 10 should be so constructed and attached to the units that their free ends are readily accessible for fixing (welding in the case described) to the wall to be insulated, after the unit has been placed in position. The fixing members are preferably attached to the units in

such a manner that their end portion which is intended for fixing to the wall projects beyond the edge of the unit.

In the form of construction described it is assumed that the edge length of the units is of such dimensions that two units per edge constitutes the suitable number. With a shorter edge length a single fixing member may be found sufficient whilst more than two units may be required for units having a relatively long edge length.

It is assumed that the units according to the invention will be constructed and supplied by a factory in a number of suitable standard dimensions and forms with the fixing members attached or without the latter. If in the case of the belt referred to above the distance between the penultimate and the first unit is less than the width of a standard unit, the last unit without fixing members may conveniently be cut to the correct size on the site. In addition to rectangular units for smooth and cylindrical surfaces, units in the form of an equal-sided parallel trapezium for conical surfaces or surfaces which cannot be developed, circular units for the poles of doubly-curved surfaces and many other forms may come into question.

Circular units may suitably be provided with three or more fixing members depending upon the size, which are arranged and uniformly distributed around the circumference.

Fig. 9 shows a part of a container 11 with a hemispherical end wall. This container is partially covered with an insulating jacket which consists of units in accordance with the invention. The illustration shows examples of different types of units which may be employed. Thus in this case a circular unit 12 is employed at the pole of the end wall. The adjacent row consists of relatively small units 13 in the form of an equal-sided parallel trapezium with relatively wide angles between the non-parallel sides. The following row which is still located on the hemispherical portion consists of similar trapezium-shaped units 14 which however, have a narrower angle and which may also be wider than the preceding ones. The next row is located on the cylindrical portion of the container, so that the units 15 employed here are rectangular. The width of the latter is primarily determined by the flexibility of the material used for the protective plate, and in other respects with due regard to the convenient manipulation of the units. Apart from this, the form and dimensions of the units may be varied as desired.

For walls forming a closed circle the units need not be arranged in closed belts as described above but may instead be fixed to the wall in a single spiral-shaped row arranged around the wall. This arrangement may be found advantageous for example, for cylindrical walls with a long axial length. In this way the necessity for using a jointing unit (9a in Fig. 4) for each turn is avoided.

The employment of units in accordance with the invention for the manufacture of insulating jackets is accompanied by the great advantage that the units can be produced on manufacturing lines in suitable standard series, after which only simple installation work remains to be carried out on the site. In this way a considerable saving in working costs is effected.

Fig. 10 shows a particularly favourable method for attaching the fixing members 10 to the unit's protective plate 6. On the protective plate, loop-shaped plate-metal strips 16 are mounted which

are suitably fixed by spot welding at P. When installing insulating coverings the end portion of the fixing member 10 is simply pushed in under the loop 16. This arrangement simplifies installation still further and facilitates transport of the ready-cut protective plates. These are very much less bulky for packing purposes without the fixing member attached to them which might also cause damage in other respects. The fixing members may suitably be packed separately.

The arrangement according to Fig. 10 may be still further developed by allowing it to serve at the same time for fastening the previously mentioned insulating mat to the protective plate. As an example of this Fig. 11 shows a loop 17 which has the same function as the loop 16 according to Fig. 10 but is provided in addition with flaps 18. The cross-section shown in Fig. 12 illustrates how the wire netting 8 referred to in connection with Figs. 1-3 is fixed to the protective plate by bending the aforesaid flaps 18 around the wire in the netting and subsequently turning them down altogether. If no fixing member 10 needs to be arranged on the other side of the protective plate, single, securely welded flaps 19 may replace the flaps 18, as shown in Fig. 12.

The method of fixing the insulating mat illustrated in Figs. 11 and 12 replaces the method, described with reference to Figs. 1-3, with the help of strips 5.

The method shown in Fig. 10 may of course also be employed for attaching the fixing member to the wall to be insulated, or it may be used as a substitute.

The invention may of course be used not only for heat-insulating jackets, but also with similar advantages for sound-insulating coverings for example. For the corresponding constructional parts of the units one is free to choose the most suitable material for each form of employment coming into question.

For sound-insulating coverings, both the walls to be insulated and the unit's protective plate are frequently constructed of a material which cannot be welded but can conveniently be glued or pasted. Furthermore, in accordance with some other method known per se, as for example by screwing, the fixing member may in such case advantageously be attached by means of a paper or woven strip which is laid over the end portion of the fixing member and glued firmly to the plate or wall, suitably by means of a synthetic resin glue such as melamine with a reacting material such as formaldehyde.

What I claim is:

1. A plurality of structurally independent units for assembling an insulating cover on a wall, each said unit comprising a cover plate, a layer of insulating material having one face thereof secured to the under face of said plate, the opposite face of said insulating layer being adapted to confront the wall, a fixing member having a good heat insulating characteristic, one end of said member being secured to the under face of said plate at one side thereof and the opposite end of said member being adapted to be secured to the wall, the side of said plate opposite that to which said fixing member is secured being adapted to interlock with that side of the plate on the adjoining unit to which the fixing member of said adjoining unit is secured.

2. The invention as defined in claim 1 wherein opposite sides of the plate on each unit are of

reverse curvature thereby to establish the said interlock between the plates of adjoining units.

3. The invention as defined in claim 1 wherein one side of the plate on each unit includes a slotted portion adapted to receive the adjacent side of the plate on the adjoining unit thereby to establish said interlock between the plates of adjoining units.

4. The invention as defined in claim 1 wherein one side of the plate of each unit is provided with a strip secured to the under face of the plate and projecting beyond the edge thereof, and the opposite side thereof is provided with a slotted portion at the under side adapted to receive the strip on the plate of the adjoining unit thereby to establish said interlock between the plates of adjoining units.

5. The invention as defined in claim 1 wherein said fixing member is constituted by two metallic end portions interconnected by an intermediate 20 non-metallic portion having a good heat insulating characteristic.

6. The invention as defined in claim 1 wherein said layer of insulating material is enclosed by a wire netting that is secured to the under face of 25 said cover plate.

7. The invention as defined in claim 1 wherein said layer of insulating material is enclosed by a metallic wire netting, a metallic strip is disposed between said insulating material and netting, and 30 said insulating material is secured to the under face of said plate by securing the said metallic strip to said plate face.

8. The invention as defined in claim 1 wherein said fixing member is constituted by two angular 35 end portions interconnected by an intermediate

portion having a good heat insulating characteristic, and the said angular end portion adapted to be secured to the wall projects beyond the edge of said cover plate.

9. The invention as defined in claim 1 wherein said cover plate includes a loop-shaped strip fixed at its end portions to the under side of the plate and which is spaced from the plate at its intermediate loop portion, and said fixing member includes an angular portion at one end thereof engaging the looped portion of said strip to thereby secure said fixing member to said cover plate.

10. The invention as defined in claim 9 wherein said layer of insulating material is enclosed by a wire netting and the end portions of said loop-shaped strip include laterally projecting flaps bent around the netting wire to thereby secure said insulating material to said cover plate.

FRIDOLF HENNING BRUNNZELL.
